UNITED STATES PATENT OFFICE.

ROY C. DOUGLAS, OF SAN FRANCISCO, CALIFORNIA.

ELECTRIC FOG-SIGNAL LIGHT.

1,077,398.

Specification of Letters Patent.

Patented Nov. 4, 1913.

Application filed October 24, 1912. Serial No. 727,565.

To all whom it may concern:

Be it known that I, Roy C. DOUGLAS, a citizen of the United States, residing at San Francisco, in the county of San Francisco and State of California, have invented 5 certain new and useful Improvements in Electric Fog-Signal Lights; and I do declare the following to be a full, clear, and exact description of the invention, such as 10 will enable others skilled in the art to which it appertains to make and use the same.

This invention relates to improvements in electric fog signal lights.

One object of the invention is to provide 15 a fog signal light of this character having an improved construction and arrangement of electrode holders and an improved means for intermittently operating one of said holders to bring the carbon electrode carried thereby into and out of engagement with the carbon electrode of the other holder.

Another object is to provide an improved 20 operating mechanism which may be adjusted to vary the length of the flash and to provide means for slowly feeding the stationary carbon toward the movable carbon.

A further object is to provide an improved grip or connection for the operating 25 mechanism of the movable carbon holder whereby should the carbon carried by this holder fail to reach the stationary carbon at the end of the downward movement of the carbon carrier said grip will automatically release the movable carbon holder or carrier 30 and permit the same to drop until the point of the carbon therein comes into engagement with the point of the other carbon and, whereby, should the stationary carbon have been fed up too far the engagement of the 35 movable carbon therewith will release said grip or connection and permit the latter to slide down on the holder or carrier of the movable carbon.

With these and other objects in view, the 40 invention consists of certain novel features of construction, combination and arrangement of parts as will be more fully described and claimed.

In the accompanying drawings; Figure 1 45 is a side view of my improved fog signal light showing the parts in the lowered or contacting position; Fig. 2 is a similar view showing the parts in the raised position as when producing an arc; Fig. 3 is a detail

cross sectional view through the operating 55 mechanism of the movable carbon taken on the line 3—3 of Fig. 1; Fig. 4 is an enlarged side view of a portion of the supporting bar for the movable carbon holder and the gripping and releasing mechanism of said bar; 60 Fig. 5 is a longitudinal sectional view of the parts shown in Fig. 4; Fig. 6 is an enlarged longitudinal sectional view of the supporting block for the stationary carbon and the feeding mechanism; Fig. 7 is a cross sectional view through the stationary carbon 65 supporting and feeding mechanism taken on the line 7—7 of Fig. 1; Fig. 8 is a side view of the operating cam for the movable electrode reciprocating mechanism; Fig. 9 is 70 a cross sectional view of said cam taken on the line 9—9 of Fig. 8; Fig. 10 is an enlarged longitudinal sectional view of one of the carbon electrode holders; and Fig. 11 is an enlarged cross sectional view of said 75 holder taken on the line 11—11 of Fig. 10.

My improved fog signal light comprises a supporting frame 1 which may be of any suitable construction and is here shown as consisting of a tubular base member 2 one end of which is connected by an elbow 3 to a socket 4 adapted to be secured to any suitable support. The opposite end of the base member 2 is engaged with a branched 80 coupling 5 one end of which is connected by a short nipple with a socket 6 which is also adapted to be secured to the support for the frame. Connected with the upper end of the coupling 5 is a tubular standard 85 7 with the upper end of which and with the outer portion of the base member 2 is connected an inclined tubular supporting and guiding member 8. In the inner side of the member 8 at a suitable distance above 90 the base 2 is formed a longitudinally disposed slot 9 the purpose of which will be hereinafter described.

Secured to the outer side of the lower portion of the supporting member 8 by bolts 100 10 is a block 11 of hard asbestos or other suitable insulating material to the outer side of which is bolted a stationary electrode supporting frame comprising a base member 12 on the upper end of which is arranged 105 an electrode guiding and supporting standard 13 having an apertured head with which the outer end of the stationary carbon elec-

trode is slidably engaged. On the lower end of the base member 12 is arranged a screw supporting standard 14 having in its upper end a bearing aperture adapted to receive the outer end of the electrode feeding screw 15 hereinafter described. Also secured to the base member 12 intermediate of its ends is an outwardly projecting guide plate 16 having in its outer end a square guiding 5 passage with which is slidably engaged to the squared stem or supporting bar 17 of the stationary electrode holder 18 in which is secured the stationary carbon electrode 19 of the light.

10 The stem or supporting bar 17 is provided with a threaded bore or passage with which is engaged the inner end of the feed screw 15 the outer end of which is revolubly mounted in the aperture of the supporting standard 14 as hereinbefore described. Fixed on the screw 15 is a ratchet gear 20 with which is engaged an operating pawl 21 pivotally mounted between links 23 the outer ends of which are pivotally connected 20 to a pawl operating rod 22. The links 23 loosely engage the screw 15 adjacent to the opposite sides of the gear 20 so that when the rod 22 is reciprocated in a manner hereinafter described the pawl will be brought 25 into successive engagement with the ratchet teeth thereby imparting a step by step movement to the gear 20 and thus slowly turning the feed screw 15 in the proper direction for projecting the stem 17 and electrode 25 holder 18 to feed the carbon electrode 19 toward the opposing electrode.

30 The rod 22 is slidably supported in a suitable guide bracket 24 secured to the member 8 of the supporting frame 1 and said rod is preferably constructed in sections which are connected by a coupling member 25 formed of suitable insulating or non-conducting material whereby any danger of the current passing through the rod 35 is obviated. The inner end of the rod is pivotally connected to the shorter end of an operating lever 26 which is pivoted near one end to the base member 2 of the supporting frame 1 and is connected near its 40 upper end with a retracting spring 27 the opposite end of which is suitably secured to the member 8 of the supporting frame 1 as shown. When thus arranged the lever 26 is adapted to be engaged by a suitable 45 tripping mechanism hereinafter described whereby the lever is actuated to reciprocate the rod 22 to cause the latter to actuate the carbon feeding mechanism in a manner described.

50 Suitably secured to the upper portion of the supporting member 8 of the main frame 1 and projecting outwardly at right angles from said member are inner and outer guide posts or standards 28 and 29 said standards 55 being connected and securely braced by a

brace bar 30. On the outer end of the post 28 is an electrode guiding and supporting sleeve 31 while on the outer end of the post 29 is a guide plate 32 having therein a rectangular passage 33 with which is slidably engaged the square stem or supporting bar 34 of the movable carbon electrode holder 35 in which the movable carbon electrode 36 is secured.

70 The carbon holders 18 and 35 each consist of a cylindrical body portion 37 having on its inner end a socket 37' in which is secured the inner end of the stem 17 of the stationary electrode or the stem 34 of the movable electrode as the case may be, said stems 80 being secured in the sockets by set screws 38. The outer portion of the body 37 of the holders is recessed to receive segmental carbon clamping members 39 which are engaged with the carbons and are inserted 85 through clamping frames 40 formed on the recessed outer portion of the body 37 of the holders, said frame having therein a clamping screw 41 which is adapted to be screwed into engagement with the outer 90 clamping member 39 thereby tightly clamping the carbons 19 or 36 whereby said carbons are securely fastened in the holders.

95 The carbon carrying or holding mechanism for the movable carbon is reciprocated to bring the movable carbon into and out of successive engagement with the stationary carbon by means of an operating mechanism comprising a bar 42 which is arranged in and has a sliding engagement 100 with the upper portion of the member 8 of the frame 1. The upper end of the bar 42 projects a suitable distance above the upper end of the member 8 and has connected thereto a grip operating fork 43 the outer 105 ends of which are connected with a gripping and releasing device 44.

110 The gripping and releasing device 44 comprises a rectangular sleeve 45 having on its upper end parallel laterally projecting bearing arms 46 and having on its sides and projecting at right angles to the arms 46 outwardly projecting stop pins 47. The sleeve 45 has a sliding engagement with the upper portions of the stem or holder supporting 115 bar 34 adjacent to the upper side of the plate 32 on the post 29. Pivotally mounted between the ends of the parallel arms 46 of the sleeve 45 are stem gripping blocks 48, said blocks being fixedly mounted on bearing pins 49 on one end of each is fixed a block operating lever 50 said levers projecting in opposite directions on opposite sides of and parallel with the sleeve 45 as shown. The outer ends of the levers 50 are connected with the upper ends of the fork 43 whereby when the latter is carried up by the operating bar 42 the levers 120 will be actuated to cause the blocks 48 to grip the stem or bar 34 of the movable elec- 125 130

trode holder and to carry said bar and holder and the movable electrode upwardly as far as the bar 42 is brought by its operating mechanism hereinafter described. 5 When the bar 42 has reached the limit of its upward movement and is released by its operating mechanism, said bar together with the gripping device and the electrode carrier or holder will drop by gravity thus bringing 10 the outer end of the electrode 36 into engagement with the point of the stationary electrode 19 thus completing the electric circuit in which the carbon electrodes are arranged. When the parts are thus operated 15 the stop pins 47 will limit the downward movement of the levers 50 as indicated in dotted lines in Fig. 5 of the drawings. When the bar 42 and the parts carried thereby drop the inner end of the sleeve 45 will be brought into engagement with the 20 plate 32 on the standard 39 and this engagement of the sleeve will operate the latter to release or disengage the blocks 48 from the stem or bar 34 and will thus permit this bar and the holder 35 to continue to drop or 25 slide through the plate 32 so that should the carbon electrode 36 be too short to reach the point of the stationary electrode 19 when the sleeve 45 engages the plate 32 said carbon will be permitted to move on until the 30 point of the stem engages the point of the stationary carbon. If, on the other hand, the stationary carbon electrode 19 has been fed too rapidly and projects upwardly to such an extent that the point of the movable carbon 35 36 is brought into engagement therewith before the sleeve 45 comes into engagement with the plate 32 the resistance caused by the engagement of the carbon 36 with the 40 carbon 19 will cause the levers 50 to disengage the gripping blocks 48 from the stem or bar 34 thus permitting the gripping device and the parts connected thereto to slip down until the lower end of the sleeve 45 45 comes into engagement with the plate 32. By thus constructing and arranging the gripping and operating mechanism of the movable electrode it will be seen that this mechanism will be automatically adjusted to 50 operatively engage the movable carbon electrode with the stationary electrode to complete the electric circuit which is immediately broken by the disengagement of the movable carbon thereby producing the arc or flash.

55 The operating mechanism for projecting the operating bar 42 for the gripping device and electrode carrier comprises a lever 51 having one end pivotally connected by a sleeve 52 to the standard 7 of the frame 1 and having 60 its opposite end pivotally connected through the slot 9 in the member 8 with the lower end of the operating bar 42. The lever 51 is connected by a link or pitman rod 53 with a trip arm 54 one end of which is pivotally

connected to a bracket 55 secured to the adjacent portion of the member 8 of the frame 1 as shown. Revolvably mounted on the outer portion of the trip arm 54 is a bearing roller 56 which is engaged with an operating cam 70 57 revolvably mounted in the bearing bracket 58 secured to the standard 7 of the frame 1 as shown. Fixed on one side of the cam 57 is a spur gear 59 which is connected by an idle gear 60 revolvably mounted in a right 75 angular extension of the bracket 58 to a pinion 61 mounted on a suitably supported shaft 62 on which is also fixedly mounted a worm gear 63. The gear 63 is operatively engaged with and driven by a worm 64 on the shaft of an electric motor 65 arranged in a suitable position on the support to which the frame 1 is secured. By providing suitably sized gears for connecting the worm 64 with the cam 57 the speed of the latter 80 may be controlled to operate the movable electrode carrier at the desired speed. 85 The cam 57 comprises a pair of similarly shaped disks 66 and 67 in one of which are formed segmental slots 68 to receive disk 90 connecting screws 69 which are engaged with the adjacent disk and thereby adjustably connect the disks 66 and 67 together in operative engagement. In one side of the disks 66 and 67 are formed substantially V- 95 shaped notches 70 one edge of which is preferably formed straight while the opposite edge is curved as shown. By thus constructing the disks 66 and 67 they may be turned on each other to increase or diminish the 100 size of the notch or recess 70 as clearly shown in dotted lines in one of the figures of the drawings. By thus varying the size of the notch or recess 70 in the cam disks the engagement of the roller 56 may be controlled to actuate the operating mechanism 105 of the carbon carrier for producing arcs or flashes of different length as will be readily understood. Arranged on and projecting laterally from one side of the disks is a trip 110 pin 71 which is carried around by the revolving movement of the disks and is thus brought into successive engagement with the free end of the trip lever 26 whereupon the latter is actuated in one direction for 115 operating the ratchet feeding mechanism connected therewith for feeding the stationary carbon electrode as hereinbefore described. The lever 26 after being tripped by the pin 71 is actuated in the opposite direction by the spring 27 as will be readily 120 understood.

The current conducting wires 72 and 73 may be connected with the carbon holders 18 and 35 in any suitable manner, said 125 wires being here shown and are preferably connected to the holders by the set screws 38 which secure the holders to their stems.

From the foregoing description taken in connection with the accompanying draw- 130

ings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

1. A fog signal light comprising a supporting frame, a stationary electrode support secured thereto, a stationary electrode holder having an adjustable engagement with said support, a stationary electrode carried by said holder, a feeding mechanism connected with said holder, a movable electrode carrier slidably mounted on said frame, a movable electrode secured in said carrier, a gripping and releasing device engaged with said movable electrode carrier, and an operating mechanism connected with said gripping device whereby the latter is actuated to retract said carrier and the electrode therein.
2. A fog signal light comprising a supporting frame, a stationary electrode support secured thereto, a stationary electrode holder having an adjustable engagement with said support, a stationary electrode carried by said holder, a feeding mechanism connected with said holder, a movable electrode carrier slidably mounted on said frame, a movable electrode secured in said holder, a gripping and releasing device engaged with said movable electrode carrier, an operating mechanism connected with said gripping device whereby the latter is actuated to retract said carrier and the electrode therein, and means to release said gripping mechanism whereby the latter and the movable electrode carrier are permitted to automatically adjust themselves to bring the electrode in said carrier into proper position with respect to the stationary electrode.
3. A fog signal light comprising a supporting frame, a stationary electrode support secured thereto, a stationary electrode holder having an adjustable engagement with said support, a stationary electrode carried by said holder, a feeding mechanism connected with said holder, a movable electrode carried slidably mounted on said frame, a movable electrode secured in said holder, a gripping and releasing device engaged with said movable electrode carrier, an operating mechanism for said movable carrier comprising a slidably mounted operating bar connected with said gripping device, a pivotally mounted lever connected with said operating bar, a trip arm connected with said lever, a cam having an operative engagement with said trip arm whereby said operating mechanism is actu-

ated to lift said movable electrode carrier and to permit the same to lower thereby disengaging and engaging the electrode therein with said stationary electrode, and means to operate said cam.

4. A fog signal light comprising a supporting frame, a stationary electrode support secured thereto, a stationary electrode holder arranged on said support, a stationary electrode secured in said holder, a movable electrode carrier slidably mounted on said supporting frame, a movable electrode secured in said carrier, a gripping and releasing device having an operative engagement with said carrier, a slidably mounted operating bar connected at one end with said gripping and releasing device, a pivotally mounted lever operatively connected with the opposite end of said bar, a pivoted trip arm having an adjustable connection with said lever, a trip roller carried by said arm, a revolvably mounted adjustable tripping cam engaged with the roller of said trip arm whereby the latter and said tripping lever and bar are projected in one direction to raise said movable electrode carrier and released to permit said carrier and electrode to drop thereby bringing the movable electrode into and out of engagement with the stationary electrode, and a motor geared to said cam.

5. A fog signal light comprising a supporting frame, a stationary electrode holder arranged thereon, a stationary electrode secured in said holder, a movable electrode carrier, having a stem, a movable electrode secured in said carrier, a suitably mounted stop plate to slidably support said stem, a gripping and releasing device comprising a sleeve having a sliding engagement with said stem, gripping blocks pivotally mounted on said sleeve to grip said stem, operating levers connected with said gripping blocks whereby they are actuated to grip said stem when the gripping device is moved in one direction, said blocks being released by the engagement of said sleeve with said stop plate when the gripping device is brought into engagement therewith, a slidably mounted operating bar having on one end a fork operatively connected with the levers of said gripping blocks whereby the latter are actuated to grip the stem of the movable electrode carrier and to thereby raise said carrier, and the movable electrode, and means to actuate said operating bar.

6. A fog signal light comprising a supporting frame having an inclined tubular member provided in one side with a slot, a stationary electrode holder arranged on said member, guide posts secured to said member, a guide sleeve on one of said posts, an apertured stop plate on the other post, a movable electrode carrier comprising a holder having a stem slidably engaged with

said apertured stop plate, a movable electrode secured in said holder and having a sliding engagement with said guide sleeve, a gripping and releasing device operatively engaged with said stem, an operating bar slidably mounted in the tubular member of said supporting frame and connected at one end with said gripping and releasing device, a lever pivoted at one end to said frame, and 5 at its opposite end to said operating bar through the slot in said tubular member of the frame, a trip arm pivotally mounted on said member and having an operative connection with said lever, a revolvably mounted 10 cam comprising a pair of disks having in one edge notches, means to adjustably connect said disks whereby the notches therein may be brought into and out of registration to a greater or less extent to increase and 15 decrease the width of the notches thereby regulating the engagement of the disks with said trip arm and controlling the length of the flash caused by the disengagement of said stationary and movable electrodes, and 20 25 means whereby said cam disks are operated.

7. A fog signal light comprising a supporting frame, a stationary electrode support secured to and insulated from said frame, a stationary electrode holder having 30 a slidable engagement with said support, an

interiorly threaded tubular stem connected with said holder, an electrode feeding screw revolvably mounted on said holder support, and having an operative engagement with said stem, a ratchet gear fixed on said screw, 35 a gear operating rod, a pawl having an operative engagement with said gear and adapted to be actuated by said rod, a spring retracted trip lever connected with said rod, a movable electrode carrier slidably mounted 40 on said frame, a movable electrode secured in said carrier, an operating mechanism connected with the latter a revolvably mounted cam engaged with said operating mechanism whereby the latter is actuated, means to revolve said cam at the desired speed, and a trip pin carried by said cam and adapted to be brought into engagement with the trip lever of the feeding mechanism for said stationary electrode 45 holder whereby said lever is operated against the resistance of said spring.

In testimony whereof I have hereunto set my hand in presence of two subscribing witnesses.

ROY C. DOUGLAS.
